UNITED STATES PATENT OFFICE

1,969,107

DISPLAY STAND

Frederick L. Stone, Denver, Colo., assignor to
Grace J. Stone, Denver, Colo.

Application April 4, 1932, Serial No. 603,021

2 Claims. (Cl. 40—146)

This invention relates to a display stand for charts, maps, graphs and other articles of similar character, particularly adapted for use in educational institutions or lecture halls.

5 It is an object of the invention to provide a portable stand of suitable height, having at its top a rack from which, in practice, the maps or charts are suspended.

A further object is to provide a rack composed 10 of a plurality of interchangeable and reversible units, which conjointly provide a display-element of large capacity.

Still another object resides in the provision of a display stand, as stated above, which is of simple 15 knock-down construction so that it may be transported by mail and assembled to an operative condition by simple methods of connection and without the necessity of employing skilled labor.

Further objects of the invention are to be found 20 in details of construction and in a novel arrangement of parts, as will be fully set forth in the course of the following description.

In the accompanying drawing, the invention has been shown in its preferred form, like characters of reference designating corresponding 25 parts throughout the views.

Figure 1 represents an elevation of the display stand,

Figure 2 is a partially broken top view of the 30 same,

Figure 3 is a transverse section of the rack at the top of the stand, taken on the line 3—3, Figure 2, and drawn to an enlarged scale,

Figure 4 is an enlarged section taken on the line 35 4—4, Figure 2,

Figure 5 is an enlarged section along the line 5—5, Figure 2,

Figure 6 is an enlarged, horizontal section, partially broken and taken on the line 6—6, Figure 40 1, and

Figure 7 is an enlarged vertical section along the line 7—7, Figure 1.

Referring further to the drawing, the reference numeral 5 designates a standard supported in a 45 vertical position by four diverging legs 6, and carrying at its upper end a horizontally extending rack.

The rack is composed of a beam 7 fastened at a median point upon the standard and projecting 50 transversely of the same in a substantially horizontal plane. The beam is rigidly held against displacement by slanting braces 8.

At the ends of the beam are relatively transversely disposed cross bars 10 which, at median 55 points, are fastened at the ends of the beam. The

cross bars are provided at their inner faces with notches 9 of rectangular section which serve as seats for a series of chart-hangers 12.

For simplicity in manufacture, the cross bars may each be composed of two sections 10a and 60 10c glued or otherwise fastened together, as best shown in Figures 4 and 5, the upper section 10a being transversely grooved to form with the lower section 10c the notched seats 9.

The chart hangers are composed of flat-faced 65 slats which at their ends fit in the notches of the cross bars and which are held against longitudinal displacement by abutment of their ends against the inner upright surfaces of the seats.

The flat faces of the hangers are parallel so 70 that maps or charts, shown at 13 in Figure 3, may be suspended at opposite sides of the hangers. The hangers may be made of soft wood so that the maps or charts can be fastened thereto by means of thumb tacks shown at 14 in Figure 3. 75 One of the charts or maps has been shown in position in broken lines in Figure 1.

It will be apparent that by the construction and arrangement of parts hereinabove described, a large number of maps or charts may be suspended from one and the same rack for display at the front thereof. A number of maps or charts may be suspended at opposite sides of the hangers, which, being reversible in their respective seats, permit of the selected display of 80 85 the maps or charts at either side thereof.

Moreover, the fact that the hangers are interchangeable makes it possible to move any one of them to the front of the rack where its maps or charts may be viewed by a class of students 90 or other audience before whom the stand is placed.

In the form of the stand shown in the drawing, four hangers each having two flat sides, provide for the suspension of eight sets of maps or charts, which may be separately displayed at the front of the stand by the simple expedient of lifting the hangers out of their seats, exchanging one for another and/or reversing their position as the case may be. 95

A large number of maps or charts may thus be assembled on one rack and kept there for any length of time without interfering with their individual use whenever required, and the stand therefore provides a safe and convenient 100 storage device as well as a device for display.

Many of the stands are at present in use in public schools and have been found to fulfill every requirement of the teachers and their pupils as well. 110

As stated hereinbefore, the stand is adapted for transportation by mail and, therefore, is of knock-down construction.

This construction as shown in the drawing, 5 and hereinafter to be described, is simple, and practical. It permits of taking the stand apart and re-assembling the same in a very simple manner without prior experience; and the form of the parts of the stand makes it possible to 10 place them together in a package of comparatively small dimensions, acceptable for transportation by parcel post.

The knock-down construction is as follows:

The four legs at the lower end of the standard 15 are of tapering form and are faced at their upper ends to be flat against the faces of the standard in a slanting position. The standard has at its lower end lengthwise extending mortises 15, and the legs have correspondingly formed 20 tenons 16 which fit into the same. The legs and the standard have registering holes to receive headed bolts 17, which, by nuts 18 screwed upon their ends, securely fasten the legs to the standard.

25 The legs are four in number and arranged in pairs opposite each other upon the four sides of the rectangular standard and the sets of registering holes of the standard and the legs, for the bolts by which the two pairs of legs are fastened to the standard, are formed one above another so that by the use of but two bolts of ordinary standard make, the four legs may be securely fastened to the standard.

The rack is supported at the upper end of the 30 standard by a tenon 19 at the upper end of the latter, inserted in a mortise in the lower side of the beam 7, and by the braces 8. The latter are fastened at opposite sides of the standard by a single bolt 20 and at the underside of the beam 35 at opposite sides of the standard, by bolts 21.

40 45 50 55

60 65

70 75

The cross bars 10 are fastened at the ends of the beam by inserting the ends of the latter into mortises 22 at the inner surfaces of the cross bars and by single screws 23.

It will thus be seen that by the use of but five 80 bolts and two screws, the parts of the display stand may be assembled into a rigid operative structure.

It is preferred to make the various parts of the stand, with the exception of the bolts and screws, of light wood, so that the stand is conveniently portable and may be sent by parcel post at little cost of postage.

What I claim and desire to secure by Letters Patent is:

1. A display stand comprising a standard, and a rack at the upper end thereof, composed of a pair of interconnected parallel bars having notched seats in their opposed faces, flat-faced 95 hangers in the seats, and charts suspended from opposite sides of the bars by tacks driven into the flat faces thereof.

2. A knock-down display rack comprising a standard, two pairs of legs having a mortise connection at the lower end thereof, two bolts fastening said pairs of legs to the standard, and a rack composed of a beam having a mortise for the end of the standard, cross bars mortised for the ends of the beam and having opposed seats, two screws fastening the cross bars to the beam, 105 braces between the beam and the standard, three bolts fastening the braces to the standard and the beam, and hangers supported in the seats, the legs, beam, cross bars, braces and hangers being formed to lie flat against the standard with 110 in the length thereof, when separated from each other and the standard, so as to provide, in association with the standard, a compact package for storage or transportation.
